AUTOMATIC COPPER TUBE CLEANER

Edward D. Horne, West Palm Beach, Fla.

Application June 20, 1938; Serial No. 214,787

2 Claims. (Cl. 15—4)

The present invention relates to tube cleaners, and has for its primary object to provide a simple and effective tool which will remove the burs and roughness on the end of a tube made in cutting 5 the tube to a required size.

A further object of the invention is to provide a tube cleaner that will automatically clean and remove burs, whether said burs occur on the outer surface or on the inner surface thereof, with 10 means also provided to govern the amount of tube cleaned.

The herein described invention finds its greatest usage in cleaning copper tubes that are used with sweat type solder fittings and includes a circular plate 15 rotatably mounted on a shaft, which shaft may be driven by any desired means. Mounted on the plate in spaced relation are a plurality of bearing members which slidably support the cleaning elements for cleaning the outer 20 surfaces of the tube. A steel cone having an abrasive surface is mounted centrally of the plate and is adapted to effectively clean and remove burs from the inner surface of the tube. The steel cone is also adapted to govern the amount 25 of surface cleaned depending upon the diameter of the tube and its position on the cone.

In order to facilitate a fuller and more complete understanding of the matter of the present invention, a specific embodiment thereof will be 30 hereinafter described, it being clearly understood, however, that the illustrated embodiment of the invention is given solely by way of example, and is essentially non-limitative upon the scope of the invention, except as expressed in the subjoined claims.

In the drawing:

Fig. 1 is a front elevational view of the new and improved tube cleaner and illustrating the brush in position for cleaning a tube.

Fig. 2 is a vertical sectional view taken on line 40 2—2 of Fig. 1, and

Fig. 3 is a sectional view through one of the cleaning elements and taken on line 3—3 of Fig. 2.

Referring to the drawing for a more detailed 45 description thereof, it will be noted that there is provided a circular plate 5 mounted for rotation on the end of a shaft 6, the shaft being adapted to be rotated by any desired means. It is to be understood that the circular plate and shaft may be integrally formed or the individual parts united by any preferred means. Mounted on the plate 50 5 and in spaced relation thereto are a plurality of bearing members 7, said members projecting laterally from the face of the plate and secured thereto by welding or other similar means. The

bearing members 7 are provided for adjustably supporting the cleaning elements for removing and cleaning the burs from the outer surface of the tube. Referring particularly to Fig. 2 of the drawing, it will be noted that an arm 8 is disposed within each member 7 and supports at its lowermost end a cleaning element in the form of a brush 9. The arms 8 extend parallel with the face of the plate 5 and, are vertically movable within the openings formed in the members 7. 5 For preventing accidental dislodgement of the arms 8 from the members 7, there is provided a cotter pin or the like 10 disposed in the upper end of each arm.

As afore indicated, the cleaning elements in the 15 form of brushes are supported on the lower ends of the arms 8 and said brushes are mounted in backing strips 11 secured to the arm 8. It is to be understood that the bristles of the brushes 8 are to be formed of a material that will readily 20 clean the surfaces of copper tubes and the like.

An adjusting plate 12 is also carried by each arm 8 and is attached thereto by means of a pin 13, and referring to Fig. 3 of the drawing, it will be noted that the lowermost portion of the adjusting plate extends above the bristles 9. It is the purpose of the plates 12 to contact the tube when it is inserted and to thereby raise the brush while centering and positioning the work. The adjusting plates 12, as illustrated in Fig. 2 of the 30 drawing, are formed with a curved front surface 14 which facilitates its sliding contact with the inserted tube 15. In other words, as the tube is inserted, the end thereof will first contact the curved surfaces 14 of the plates 12, and further 35 insertion of the tube will cause the plates 12 and arms 8 to be raised carrying with them the brushes 9. When the tube is finally positioned for cleaning, the brushes 9 will rest against the outer surface thereof and the plates 12 will be 40 cut off engagement with the tube.

A coil spring 16 encircles each arm 8 and is positioned between the pin 13 and member 7 respectively. The coil spring 16 exerts a constant pressure downwardly on the cleaning elements 9 45 thereby assuring constant contact of the brushes with the tube.

As hereinbefore pointed out, in the cutting of the tubes, burs quite frequently occur on the inner surface and end thereof and the present invention provides a means of cleaning and removing the inner surface burs simultaneously with the cleaning of the outer surface. The means for accomplishing this purpose includes a steel cone 16' attached to the inner surface of the plate 55

5 and preferably disposed in the central portion thereof. The cone 16 is provided with stepped portions 17 which portions have roughened edges for contact with the inner surface of the tube.

5 By provision of the stepped portion 17 on the cone 16, it is possible to clean tubes of various sizes and also to govern the amount of the outer surface of the tube to be cleaned. The cone as disclosed in Fig. 2 of the drawing, is adapted to 10 function with tubes of three sizes, the largest size tube being illustrated in phantom and resting upon the uppermost step and thereby abutting the inner surface of the circular plate 5. Should a size smaller tube be cleaned the same would rest 15 upon the middle step and in view of the width of each step, the smaller the tube being worked upon the smaller the amount of outer surface being cleaned. This feature is readily understandable from an inspection of the drawing.

20 It may be desired to house the various working parts of the device and for accomplishing this purpose there is provided a protecting plate 18 preferably circular in cross section and attached to the plate 5 by any desired means. The plate 25 18 forms a housing, thus protecting the various parts from dirt and injury.

From the above description it is believed that the operation of the device is readily apparent. A tube 15 is inserted between the plates 12 which 30 will raise the brushes, against the tension of the springs 16, until said tube is in abutting relation with the face of the plate. After the tube has been positioned on the cone 16', the circular plate 5 through the shaft 6 is rotated carrying with it 35 the brushes 9 and cone 16'. Constant rotation will effectively remove burs and the like from the outer and inner surfaces of the tube, thereby preparing the same for a sweat type solder fitting.

It is to be understood that this improvement 40 is capable of extended application and is not con-

fined to the exact showing of the drawing nor to the precise construction described and, therefore, such changes and modifications may be made therein as do not affect the spirit of the invention nor exceed the scope thereof as expressed in the appended claims.

What I claim as new is:

1. A tube cleaner of the character described comprising, a plate, means for rotating said plate, means carried by and extending laterally of said plate for slidably supporting cleaning elements in spaced relation thereon, means for guiding the tube into position for cleaning, means for maintaining said cleaning elements and guide means in contact with the tube being cleaned, an abrasive element coaxially related to the axis of rotation of said plate, with said plate rotating in a plane at right angles to the axis of the tube being cleaned, and means on said abrasive element adapted to support one end of the tube and to 20 clean the inner surface thereof.

2. A tube cleaner of the character described comprising, a rotary plate, arms extending laterally of said plate and arranged in spaced relation thereon, each arm supporting a member slidably therein and disposed substantially parallel to the face of said plate and radiating from the center thereof, a brush element carried by one end of each of said members, guide means for said tube carried by each of said members and substantially parallel with said brush elements, and an abrasive element coaxially related to the axis of rotation of said plate, with said plate rotating in a plane at right angles to the axis of the tube being cleaned, said abrasive element being substantially cone-shaped with a stepped surface for supporting one end of various sized tubes and to 35 clean the inner surface thereof.

EDWARD D. HORNE. 40
